UNITED STATES PATENT OFFICE.

DAVID W. EMSLIE, OF CLEVELAND, OHIO.

DOORSTOP.

Application filed November 16, 1922. Serial No. 601,280.

To all whom it may concern:

Be it known that I, DAVID W. EMSLIE, a citizen of the United States, residing at Cleveland, in the county of Cuyahoga and 5 State of Ohio, have invented certain new and useful Improvements in Doorstops, of which the following is a specification.

This invention relates to door stops or checks, of the type attached to the floor and 10 adapted to engage a door when desired, for the purpose of holding the door in partly open position, and preventing it from being either opened to a greater extent or closed entirely.

15 The device is illustrated in the accompanying drawings in which Fig. 1 is a top plan view of the device, the door and its casing being shown in section. Fig. 2 is a side elevation of the device, with the door 20 in section. Fig. 3 is an enlarged top view of the device. Fig. 4 is a section on the line 4-4 of Fig. 3. Fig. 5 is a section on the line 5-5 of Fig. 3.

In the drawings, 6 indicates a swinging 25 door, which may be provided with a strike plate 7 at its lower edge.

The stop or check includes a base plate consisting of a head piece 8 and a tail piece 9 connected by bar 10 and attached to the 30 floor as by screws 11. Fastened to the head piece is a bearing piece 12 and fastened to the tail piece is a bearing piece 13, the bearings in which receive trunnion extensions 13 and 15 on a wedge-shaped latch plate 16. 35 The bearing piece 12 has at the inner edge thereof an upright notch 16^a and two lateral or side notches 17, and a spring 18 is coiled around the trunnion 15, between the tail bearing and the body of the latch, and tends 40 to force the latter forward so as to engage its opposite edge in one or the other of the notches 16^a and 17.

By pressing the latch backwardly against the tension of the spring it may be disengaged from the notch 16 and then turned 45 down on its side to lie parallel with the floor and engage with one of the notches 17, to hold it in inoperative position. Or it may be turned up to vertical position, and engaged in notch 16^a as shown in the drawings, in which position it will act as a stop 50 for the door. If the door is inside of the latch, it will prevent the door being opened fully. If outside of the latch, it will prevent the door closing. It will therefore be 55 useful either to prevent a person entering the door, or to prevent the full closure or slamming of the door. But by kicking the latch with the foot it may be allowed to turn down so that the door will swing over 60 it to open or closed position.

Various changes may be made in the details of the device, within the scope of the following claim:

I claim:

A door stop comprising a base plate having spaced bearings, a rocking latch plate having trunnions slidable in said bearings, said latch plate being mounted between the bearings, one of said bearings having a notch 70 at the top to hold the plate in upright position, and another notch at the side to hold the plate when swung down, and a spring coiled around one of the trunnions between the plate and one of the bearings and tending to force the plate into engagement with either of the notches. 75

In testimony whereof, I affix my signature in presence of two witnesses.

DAVID W. EMSLIE.

Witnesses:

JOHN A. BOMMHARDT.
ROBERT BOWIE.
